(57) **CLAIM**

The ornamental design for a “lap stand for portable electronic devices,” as shown and described.

DESCRIPTION

FIG. 1 is a perspective view of a lap stand for portable electronic devices, showing my new design;

FIG. 2 is a front elevational view thereof;

FIG. 3 is a rear elevational view thereof;

FIG. 4 is a left side elevational view thereof, the right side elevation view being a mirror image thereof;

FIG. 5 is a left side cross-sectional view thereof taken from line 5-5 on FIG. 1, the right side elevation view being a mirror image thereof;

FIG. 6 is a top plan view thereof;

FIG. 7 is a bottom plan view thereof;

FIG. 8 is a side elevational view showing a tablet computer in a first position on the lap stand;

FIG. 9 is a side elevational view showing a tablet computer in a second position on the lap stand; and,

FIG. 10 is a side elevational view showing a tablet computer in a third position on the lap stand.

The broken line showing of a tablet computer is for environmental purposes only and forms no part of the claim.
